[57] **CLAIM**

The ornamental design for a food processing table, substantially as shown and described.

DESCRIPTION

FIG. 1 is a front perspective view of a food processing table showing my new design;

FIG. 2 is a bottom plane view thereof;

FIG. 3 is a side elevational view thereof;

FIG. 4 is a side elevational view thereof taken from the side opposite that shown in FIG. 3; and

FIG. 5 is a rear elevational view thereof.

The member positioned adjacent the wire basket is a slidable board containing slots to receive utensils such as food processor blades.
